UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-YOKE FOR RAILWAY-CARS.

1,284,754.

Specification of Letters Patent. Patented Nov. 12, 1918.

Application filed March 23, 1917. Serial No. 156,919.

To all whom it may concern:

Be it known that I, JOHN F. O'CONNOR, a citizen of the United States, residing at Chicago, in the county of Cook and State of Illinois, have invented a certain new and useful Improvement in Draft-Yokes for Railway-Cars, of which the following is a full, clear, concise, and exact description, reference being had to the accompanying drawings, forming a part of this specification.

My invention relates to improvements in draft yokes for railway cars.

The object of my invention is to provide a simple and strong connection between the draft yoke and the draw bar.

In the drawings forming a part of this specification, Figure 1 is a side elevation of a draft rigging embodying my invention. Fig. 2 is a cross section, taken on line 2—2 of Fig. 1. Fig. 3 is a cross section, taken on line 3—3 of Fig. 1, and Fig. 4 is a perspective view of the lower cap.

Referring to the drawings, the numeral 10 indicates a yoke strap of a usual U-shaped form and adapted to surround a draft gear, as will be readily understood. The numeral 11 indicates a draw bar, the same being provided with the usual upper and lower shoulders 13 and 14, respectively. The yoke strap in its upper and lower limbs 15 and 16, respectively, is vertically perforated near its forward ends with the usual rivet holes 17—17. An upper cap 18 is associated with the upper limb 16, the said upper cap comprising a plate 19 provided on either side with the angular flanges 20—20 adapted to extend along the sides of the forward end of the yoke limb 15. The said plate 19 forms a head for the preferably integral bolt 22, or, if preferred, bolts 22—22, as shown in Fig. 1 of the drawings, the said bolts extending at their opposite ends through the perforations 17 in the lower limb 16 of the yoke strap and through suitable perforations 24—24 provided in the lower cap 25. The said lower cap 25 comprises a plate 26 with the angular side plates 27, and each of said caps, the upper and lower, is provided near its forward ends with the inturned flanges 30.

The said flanges 30 are, except as herein-after described, spaced apart from the forward ends of the yoke limbs 15 and 16, as

indicated at the numerals 31—31 in Fig. 1 of the drawings. This spacing is provided in order that roughened yoke ends or irregular spacing of the perforations in the yoke in reference to said ends may not prevent the easy assembling of the draw bar yoke and yoke caps. The said flanges 36, near their inner ends, are provided with abutments or shoulders 37 which are adapted to engage the draw bar shoulders 13. By reason of the spacing, as indicated at 31, and as above described, a direct abutment between the said shoulders 37 and the draw bar shoulders is insured.

It will also be noted that by reason of the construction of the caps having shoulders 70 engaging the draw bar shoulders along the inner faces of the yoke limbs and plates along the outer faces of the yoke limbs, the bolts, or any equivalents thereof that may be employed, are placed in double shear at each 75 end thereof.

The said bolts, as shown in the drawings, are provided with suitable threads 39 at their ends and nuts 40 and with means, as for instance, the cotters 41, to prevent their 80 accidental displacement from the bolts.

I claim:

1. The combination with a draw bar having shoulders and a yoke strap to be connected thereto, of means passing through the draw bar and yoke strap, of yoke caps associated with said means, said caps engaging the draw bar shoulders along the inner faces of the yoke strap and being connected with said means on the outer faces of the yoke 90 strap.

2. The combination with a draw bar having shoulders and a yoke strap, of connecting means passing through same, and caps engaging said connecting means along the outer faces of the yoke strap and engaging the shoulders of the draw bar along the inner faces of the yoke strap, the said caps being spaced apart from the ends of the yoke 95 strap.

3. The combination with a draw bar having upper and lower transversely extending shoulders and provided with rivet holes, of a yoke having rivet holes aligned with the rivet holes of the draw bar, upper and lower 105 caps fitting over the ends of the arms of the yoke, said caps having shouldered engagement with the transverse shoulders of the

draw bar, and means, extending through the alined holes of the yoke and draw bar, detachably clamping said caps in position.

4. The combination with a shouldered draw bar and yoke strap having the usual alined rivet receiving holes, of devices for detachably connecting the draw bar and yoke, said devices including a pair of caps, each cap having a horizontal wall, a vertical

transverse wall, and spaced vertical side walls, and means extending from one cap to the other cap through said alined rivet receiving holes, said means detachably holding said caps in position.

In witness that I claim the foregoing I 15 have hereunto subscribed my name this 20th day of Mar., 1917.

JOHN F. O'CONNOR.
